UNITED STATES PATENT OFFICE

HARRY CLEMENT RITCHIE, OF LIVERPOOL, ENGLAND

REINFORCED-CONCRETE STRUCTURE

Application filed January 12, 1926, Serial No. 80,775, and in Great Britain January 15, 1925.

This invention relates to improvements in reenforced concrete structures, and more particularly to such structures in which the metallic reenforcement itself forms a rigid self-supporting structure adapted to carry the constructional loads including the load of wet concrete moulded in situ to form the composite structure.

In my said specification I have described a construction in which this difficulty is overcome by forming the longitudinal tensile reenforcement entirely of round bars, embedded in the concrete, and connected to the other or compressive reenforcement by transverse 15 bracings and struts; the object of the present invention is to employ as reenforcing members structural sections as I beams, or built-up lattice girders, adapted to form the self-supporting structure, and to strengthen them by 20 a round bar or bars so disposed and connected to the two flanges or booms of the beam or lattice that, in the composite structure, the tensile and compressive strength of the beam or lattice, the round bars, their connecting 25 rods or stirrups and the concrete are, in accordance with the rules which obtain in standard practice utilized to the fullest extent to meet the stresses to which the structure is subjected.

According to the present invention I form the rigid self-supporting structure of a structural section beam or built-up lattice, and I strengthen each of the main longitudinal flanges or booms of the beam or lattice, which 35 is subject to tensile stress, by means of a longitudinal bar or bars embedded in the concrete on the side of the said flange or boom remote from the neutral axis, and I connect the bar or bars to the beam or lattice, and connect 40 the flanges of the beam or lattice together by means of laterally disposed transverse stirrups or rods embedded in the concrete and passing through the said flanges, said rods forming the necessary reenforcements.

The respective stirrups or rods may embrace the respective bars and pass through and be fixed axially to the two main longitudinal reenforcements, the said rods or stirrups being embedded in the masses of concrete 50 between the said reenforcements; or the bars

of each group may, according to one modification, be connected together by means of pairs of saddles through which pass and to which are attached the screw-threaded ends of the respective transverse rods, the saddles being 55 clamped on the bars by nuts on the said ends.

When each of the flanges or booms of the beam or lattice is subjected to tensile stresses as in a column, arch, or beam carrying a moving load, there is arranged in respect to each 60 of the said flanges or booms a group of bars embedded in the concrete on the side of the flange remote from the neutral axis, the groups of bars and said two flanges being connected together by laterally disposed 65 transverse stirrups or rods passing through the said flanges or booms and embedded in the concrete between them.

In the case of columns subjected to bending in two directions, one parallel with and the other at right angles to the plane of the web of the beam or lattice, the column is strengthened to resist the latter bending action by means of two groups of bars respectively 70 located in the concrete on the sides of the beam or lattice remote from the plane containing the neutral axis and the said web.

The invention also comprises other improvements as described and claimed herein.

I have illustrated my invention in the 80 accompanying drawings in which:—

Figs. 1 to 5 show the arrangement as applied to the reenforcement of beams;

Fig. 1 being an elevation;

Fig. 2 a corresponding transverse section;

Fig. 3 a view similar to Fig. 2 showing a lattice structure;

Fig. 4 a view similar to Fig. 2 but showing three round bars.

Fig. 5 a perspective view of a part of the arrangement of Figs. 1 and 2.

Figs. 6 and 7 show the invention applied to a column.

Fig. 6 being an elevation, and

Fig. 7 a transverse section.

Fig. 8 which is a transverse section shows the arrangement applied to a vertical counterfort or buttress for a wall, and Fig. 8A shows a modification of Fig. 8.

Figs. 9 and 10 show the invention applied to the reenforcement of an arch.

Fig. 9 being an elevation.

Fig. 10 a longitudinal section.

5 Figs. 11 to 13 which are fragmentary transverse sections, show arrangements for supporting the box in which the concrete is moulded.

In the drawings the concrete, indicated by 10 the reference letter C, is added in the usual manner to form the completed structure and is represented in the usual conventional manner.

Referring first to Figs. 1 to 5:—

15 Figs. 1 and 2 represent the reenforcement of a beam comprising a steel girder of I-shaped section, which girder O is capable of carrying the constructional loads and wet concrete before referred to, but which without 20 reenforcement is incapable of carrying full normal load.

25 Reinforcement is added in the form of longitudinal bars a placed as shown on the side of the tension flange o^2 remote from the neutral axis; and transverse stirrups or reenforcement at right angles to the neutral axis p^1 embracing the bars a , and passing through 30 holes provided in the flanges of the beam O, and being hooked or otherwise secured at 35 their ends q to the top flange o^1 the bars a being thus suspended at a suitable distance below the flange o^2 and held against lateral displacement.

The stirrups may take the form of split 35 pins p^1 as shown in Fig. 2, or of "eyed" rods p^2 as shown in Fig. 3, and the eyed ends i may be shaped so as to serve in conjunction with the holes in the lower flanges of the I-section O as spacers to hold the bars away from the 40 underside of the flanges and so allow the concrete to completely surround the bars.

The rods or bars a are bent up at s and hooked at their ends w , Fig. 1, as required, in the ordinary manner of rod reenforcement, 45 the lower flanges o^2 of the I-shaped section O being holed or notched as at s^2 , so that the said rods may pass up from below the said flanges in an approximately vertical plane, into the body of the concrete which is finally 50 added to complete the structure. The hooked ends of the bars a may be secured to the top flanges o^1 of the I-section by means of split pins s^1 .

The stirrups p^1 or the rods p^2 embracing 55 the bars a and passing through the flanges of the I-shaped section O afford the necessary mechanical bond between the flanges of the said section and the concrete, and at the same time connect the rod reenforcement a to the 60 said I-section independently of the concrete.

The longitudinal spacing of the stirrups or rods is usually not greater than the depth of the girder O, but they may frequently be 65 more closely spaced so as to stiffen the web of the said girder and thereby increase the

resistance to shear off the final reinforced concrete structural member.

It will further be seen that the stirrups or rods p^1 or p^2 pass through the flanges and the rectangular masses of concrete located between the flanges of the beam and thus prevent shear between the said masses of concrete and the beam; the stirrups or rods thus arranged also act in conjunction with the concrete to stiffen the web of the beam.

In Fig. 3 the built-up lattice T replaces the I-section shown in Figs. 1 and 2, the remainder of the reenforcement being similar to that shown in the latter figures. The stirrups or saddles in this case are shown 30 as rods p^2 with eyed ends i and are screw-threaded at the top to take securing nuts u .

In the cross-section, Fig. 4, a beam O' similar in construction to that shown in Fig. 2 is employed, but with three bars a added instead of two. In this case pairs of saddles b^1 and b^2 are used to hold the bars rigidly apart, and transverse members d similar to p^2 pass through the holes in the saddles and holes in the flanges of the I-section as shown, 90 being anchored at top and bottom by means of nuts u and u^1 , the saddles being tightened to grip the bars by the tightening nuts u^1 and u^2 .

Fig. 5 is an isometric view on a larger scale, 95 a part of the reenforcement of a beam such as that shown in Figs. 1 and 2, both forms of stirrups p^1 and p^2 being shown.

Figs. 6 and 7 show one mode in which the invention may be applied to a column construction; in this case an I-shaped section steel stanchion V capable of carrying the construction loads only is reenforced by round bars; the section of the stanchion V illustrated is assumed to be so loaded that it does 100 not need to be reenforced to prevent bending in a direction parallel with the line x , x ; should it need such reenforcement only, round bars would be fitted, arranged as shown in Figs. 1 to 5 but with the arrangement duplicated, that is to say with bars a arranged in respect to the flange o^1 (Fig. 2) in the manner shown in respect to the flange o^2 . Such 105 duplicate reenforcement is shown in Figs. 8 and 10, hereinafter described.

The bars a^1 Figs. 6 and 7 to stiffen the column with reference to the neutral axis x , x , are fitted on the sides of the stanchion remote from the said axis, and are connected to the flanges v^1 and v^2 by means of saddles m , which saddles are caused to grip the bars and the flanges by means of nuts u and u^1 and collars or nuts u^2 on the rods d .

Additional transverse reenforcement may be provided in the form of stirrups or wire binders y , spaced at suitable intervals vertically, and fixed round the stanchions, which binders need not necessarily in this case be connected to the other parts of the structure except by means of the concrete which is final- 110 115 120 125 130 135

ly placed to complete the reenforcement of the column.

The form of reenforcement illustrated in Figs. 8 and 10 and hereinafter described as applied to buttresses and arches respectively, 5 may also be employed in the case of columns in addition to the reenforcement by the bars a^4 as described in reference to Fig. 7.

Fig. 8 shows the application of the invention to the reenforcement of a vertical counterfort or buttress for a wall. The details of construction are as already described for beams wherein a built-up lattice girder is employed as in Fig. 3, except that reenforcement bars a^4 are added to both booms of the rigid initial structure T' provided to carry the constructional loads; Fig. 8A shows a similar construction except that as in the case of column or stanchion reenforcement 15 additional bars b^4 and stirrups or binders y^4 may be employed with the concrete to complete the reenforcement of the final structure.

Figs. 9 and 10 show the invention as applied to the reinforcement of an arch.

The details of construction are similar to those already described for beam and buttress construction wherein reenforcement bars a are added to both T 's t which form the top and bottom booms of the initial lattice steelwork structure which is thus reenforced by the bars a , the stirrups or rods p , and the concrete which is finally placed to form the complete reenforced structure required. Reenforcement as shown in Figs. 6 and 7 illustrating column construction may also be employed in arch construction.

Fig. 11 illustrates how the temporary mould may be suspended from the fabricated reenforcement. In this figure strip metal hangers 1 of shape shown pass over and hang on to the lowest layer of bar reenforcement. These metal strips are bent at the ends 2 as shown, the ends being holed to take a nut and bolt 3. The bolts 3 carry the bottom member 4 of the mould, which member in turn carries the side members 5, sheeting 6 being carried on transverse members 7 supported by cleats 8.

In Fig. 12 the transverse members d are 50 provided with a threaded extension e below the eye i , (also shown to larger scale in Fig. 5). In this arrangement of the mould the bottom member 4 carries the side members 5 which are tied together at the top by cross members 9.

In Fig. 13 where the reenforcement is partly made up of a bar t , through the pins f^1 are provided at suitable intervals and may be bent as shown. Where an I or other section 60 with continuous web is employed the web is holed as required to pass the pins f^1 .

The centering or moulds for the concrete employed need not necessarily be of timber construction and any other or suitable material such as sheet steel or the like may be

used. Further the centering of whatever character may be suspended in any convenient manner from the rigid steel structure.

In the foregoing specification where round rods or bars are referred to, oval, polygonal 70 or other similar section rods may be used, and where desired such rods may be provided with projections, indentations or any other form of mechanical bond.

Having now fully described my invention, 75 I declare that what I claim and desire to secure by Letters Patent is:—

1. In combination in a composite structure of steel and concrete of the type herein referred to, a rigid self-supporting reenforcement comprising a main member, a longitudinal bar embedded in the concrete on the side of the main longitudinal tensile flange of said main member remote from the neutral axis of said main member to strengthen said tension flange, reenforcing means disposed at right angles to the neutral axis and passing through the flanges of said main member to connect said bar to the main member and to connect the flanges of the main member together, substantially as described. 85

2. In a structure constructed in accordance with claim 1, said reenforcing means being so disposed that the longitudinal bar is embraced thereby, said means passing through both flanges of the main member, substantially as described. 95

3. In a structure constructed in accordance with claim 1, a plurality of said longitudinal bars, pairs of saddles connecting the bars of a group, and respective reenforcing rods having screw threaded ends and passing through said saddles, said saddles being clamped on the bars and connected to said rods by nuts on said ends, substantially as described. 100

4. In a structure constructed in accordance with claim 1 in which each of the main flanges of the main member is subjected to tensile stress, a group of bars disposed in respect to each of said flanges on the sides of the flanges remote from the neutral axis, and embedded in the concrete, the groups of bars and said flanges being connected together by reenforcing means passing through the said flanges and embedded in the concrete between them, substantially as described. 110

5. In a structure constructed in accordance with claim 1 and subjected to bending in two directions, one parallel with and the other at right angles to the plane of the web of the main member, two groups of bars respectively disposed in the concrete at the sides of the main reenforcement remote from the plane containing the neutral axis and the said web, said bars reenforcing the main member to resist the latter bending action. 120

6. In a structure constructed in accordance with claim 1, said longitudinal reenforcing bars being so disposed that they are spaced apart a distance less than the width 130

of the flange of the main members, said flange having holes or notches through which the bent ends of the said bar pass into the concrete on the side of the reenforced flange 5 nearest to the neutral axis, substantially as described.

In testimony whereof I set my hand.

HARRY CLEMENT RITCHIE.
